(57) **CLAIM**

The ornamental design for a combined dispenser and holder for beverage bottles, as shown and described.

DESCRIPTION

FIG. 1 is a front plan view of a dispenser and holder for beverage bottles showing my new design;

FIG. 2 is a right side elevational view thereof, which is symmetrical with a left side elevational view thereof;

FIG. 3 is a back side plan view thereof;

FIG. 4 is a bottom side plan view thereof;

FIG. 5 is top side plan view thereof; and,

FIG. 6 is a right side elevational view thereof holding a beverage bottle, said beverage bottle is shown in phantom and no claim is made to said bottle or the term "SODA" appearing on said bottle. The beverage bottle and the term "SODA" is shown for illustrative purposes only.
